CLAIM

The ornamental design for a combined menu and tray support or the like, substantially as shown and described.

DESCRIPTION

FIG. 1 is a front elevational view of a combined menu and tray support or the like showing my new design; FIG. 2 is a side elevational view taken from the right of FIG. 1;

FIG. 3 is a top plan view thereof;

FIG. 4 is a side elevational view taken from the left of FIG. 1, the portion of a support pipe being shown in broken lines for illustrative purposes only;

FIG. 5 is a rear elevational view thereof; and

FIG. 6 is a bottom plan view thereof.
